THREAD TRIMMING MECHANISM FOR
SEWING MACHINES

Edward P. Spaine, Bridgeport, Conn., assignor to
The Singer Manufacturing Company, Elizabeth, N. J., a corporation of New Jersey

Application October 22, 1948, Serial No. 55,894

12 Claims. (Cl. 112—252)

1

This invention relates to sewing machines and more particularly to an improved thread-trimming mechanism adapted for an adjustable automatic group-stitch sewing machine of the buttonhole type, which thread-trimming mechanism will cut and hold the needle-thread between sewing periods, releasing the needle-thread at the beginning of a sewing operation and so controlling the needle-thread that the beginning end thereof will be drawn down flush with the work.

Adjustable machines have been produced for sewing buttonholes of various lengths. In these machines the stitch-forming mechanism or the work-holder travels over a fixed maximum distance, and adjustable means are provided to control the position in said travel where the stitch-forming mechanism is started and stopped. The needle-thread trimmer in these machines may be constructed in accordance with the disclosure in my U. S. Patent No. 2,301,798, November 10, 1942, and preferably is located in a position such that at the end of the sewing operation the lead of the needle-thread from the last stitch in the work to the eye of the needle lies within the range of movement of the trimmer. If it is desired to cut the needle-thread at the end of the rapid feed instead of when the stitching mechanism is first stopped, the lead of the needle-thread becomes important as to whether the needle-thread is severed. For example, when the machine is set to sew the longest buttonhole within the range of the machine, the lead of the needle-thread at the end of the stitching operation is such that the thread is readily straddled by the two relatively movable cutting members of the thread-trimmer as the trimmer device moves into thread severing position. When the machine is adjusted so that it produces a very short buttonhole, the lead of the needle-thread is not as favorable to the trimmer as it is when the machine is set to sew a long buttonhole. It happens occasionally that when the thread-trimmer moves into thread-severing position the thread is missed and consequently not cut by the trimmer. If the thread-trimmer is set to unerringly cut the needle-thread when the machine is adjusted to sew the shortest buttonhole within the range of the machine, there is the possibility of missing the needle-thread when the machine is adjusted to sew the longest buttonhole within the range of the machine with the same setting of the trimmer device.

It is the primary object of the present invention to provide a thread-trimming mechanism which will unfailingly sever the needle-thread of

2

an adjustable automatic group-stitch sewing machine regardless of the direction of lead of the needle-thread from the last stitch in the work.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Of the accompanying drawings, Fig. 1 is a left side elevation of a buttonhole sewing machine embodying the invention.

Fig. 2 is a front end elevation of the machine with the bracket-arm and the lower plates of the work-holder in transverse section.

Fig. 3 is a horizontal section through the bracket-arm standard of the machine, showing the thread-trimming mechanism in elevation.

Fig. 4 is a section taken substantially along the line 4—4; Fig. 3.

Fig. 5 is an enlarged perspective view of the trimming device and its actuating connections showing, in full lines, the device in its normally closed or inoperative position and, in dotted lines, the thread-cutting knife in its open position preparatory to its advance into needle-straddling position.

Fig. 6 is a view similar to Fig. 5, but showing, in dotted lines, the thread-trimmer in needle-straddling position and, in full lines, the thread-trimmer in closed position after having moved into its lowermost position below the needle.

Fig. 7 represents a section taken substantially along the line 7—7; Fig. 5.

Fig. 8 is a plan view of the thread-cutting members with the cover-plate removed to show the pivotal support of the movable-knife-element.

Fig. 9 is an enlarged transverse section of the thread-cutting and thread-nipping blades, showing the needle-thread after it is cut with the beginning end nipped.

Referring more in detail to the drawings, the invention is shown as embodied in a buttonhole sewing machine having, in general, constructive features which are substantially in accordance with the disclosure in the U. S. patent of E. B. Allen, No. 15,324, reissued April 4, 1922. The machine is constructed with a frame having a bed 20 from one end of which rises a standard 21 of an overhanging bracket-arm 22 terminating in a head 23.

The stitch-forming mechanism is constructed

substantially in accordance with the disclosure of U. S. Patent No. 1,372,473, dated March 22, 1921, and comprises the usual upper endwise reciprocating and laterally vibratory needle 24 and underthread handing devices including threaded and non-threaded loopers 25 and 26 and loop-retainers 27 and 28 (Fig. 2), which upper and under stitch-forming devices are mounted to turn about a vertical axis, as in placing the stitches radially about the eyelet-end of a buttonhole and between sewing periods to restore the stitching devices to their initial position. The means to so turn the stitch-forming devices comprise the usual upper and under sector-gears 29 and 30 each having arms 31 and 32 connected by links 33 and 34 to rock-arms 35 and 36 carried on the opposite ends of a vertical shaft 37. The vertical shaft is oscillated by a cam-follower roll (not shown) entering a suitable stitch-rotating cam-groove formed in the bottom face of a feed-wheel 38 (Fig. 1). The stitch-forming devices are driven by the main sewing shaft 39, the period of operation of which is controlled by a stop-motion device which includes the usual tilting stop-motion lever 40 (Fig. 1) fixed on the rock-shaft 41 to which is fixed an arm 42. The arm 42 is connected by a limb 43 to a lever 44 fulcrumed on the bed 20 at 45 and carrying a follower-nose 46 in position to be engaged by the "start-sewing" cam 47 adjustably secured on a pattern wheel 48 fixed to a cross rotary shaft 49 which is geared to and runs one-to-one with the feed-wheel 38. The pattern wheel is also formed with a "stop-sewing" drop-off cam 50 which, when it travels past the follower-nose 46, permits a coil-spring 51 to snap the stop-motion lever 40 into stop position, shown for example in Fig. 1.

The work-clamp is of the traveling type. It is first rapidly moved over the bed 20 to carry the work forwardly from initial or buttonhole-cutting position to stitching position, then more slowly moved in step-by-step fashion to place the stitches about the buttonhole, and then rapidly returned to initial position. The work to be sewn is held through the entire cycle in the work-clamp which includes the lower clamp-plates 52 and upper clamping feet 53. The lower clamp-plates are carried by the usual cross-slide 54 (Fig. 2) which is adapted to slide laterally of the machine-bed 20 on a longitudinal slide-frame 55 shiftable in ways longitudinal of the machine-bed. The work-clamp is given its longitudinal travel and lateral components of its feeding movement by suitable lever-connections with the feed-cam 38 mounted in the bed 20 of the machine and driven at a rapid rate prior and subsequent to the sewing period by the cross rotary shaft 49 which receives power from a rapid-feed shaft 56 (Fig. 1) through an automatically controlled clutch (not shown). The lever-connection, together with the automatically controlled clutch, are constructed substantially in accordance with the disclosure of said U. S. Re-issue Patent No. 15,324. The feed-cam 38 is more slowly driven during the sewing operation by a suitable gear-train, indicated generally as 57 in Fig. 1, actuated from the main sewing shaft 39, the period of operation of which is controlled by the stop-motion device 40, all in the manner fully disclosed in the above mentioned Reissue Patent No. 15,324. As previously mentioned, means is provided for automatically throwing the stop-motion lever 40 into and out of operation to start and stop the stitch-forming mechanism, the

control trips 47 and 50 for the stop-motion lever being adjustably secured on the pattern wheel 48 carried on the cross rotary shaft 49.

As previously mentioned, buttonhole sewing machines of the type herein disclosed have been produced for sewing buttonholes of various lengths and in these machines the work-holder travels over a fixed maximum distance. Adjustable means are provided to control the position in said work-holder travels where the stitch-forming mechanism is started and stopped. In the present case, these means are the cam-elements 47 and 50, both of which are adjustably secured on the pattern wheel 48. The pattern wheel is detachably fastened on the cross rotary shaft 49 and can be readily removed and replaced by a universal pattern wheel such as disclosed in my U. S. Patent No. 2,301,797, issued November 10, 1942, when it is desired to fit the machine for a wide range of buttonhole sizes. It will be appreciated that the direction of lead of the needle-thread from the needle to the last stitch of a completed buttonhole may vary with the length of a completed buttonhole and to provide a needle-thread trimmer which will unerringly sever the thread regardless of its direction of lead, I have invented a thread-trimmer which advances into an intermediate needle-straddling position in its travel from inoperative or retracted position to thread-cutting position. The advantage of this action is that the needle-thread is positively disposed between the cutting elements of the trimmer by virtue of the fact that the two cutting elements of the trimmer approach the needle and straddle it with one of the elements on either side of the needle blade, after which the cutting elements drop below the point of the needle and close on the thread to sever it. Obviously, in straddling the needle the thread carried thereby is introduced between the cutting elements and when the cutting elements drop into cutting position below the needle the thread is properly located between the cutting elements and is severed.

The details of my improved thread-trimmer are best illustrated in Figs. 5 and 6. The device is preferably constructed as a detachable unit and comprises a bracket or base 58 secured by screws 59 and 60 (Fig. 3) to the lower end of the usual stationary pivot-stud 61 of the needle-turning sector-gear 29. Secured, as by screws 62, to the front end of the base 58 is an angle-bracket, indicated generally as 63, having a depending vertical limb 64 to which is fulcrumed at 65 a carrier-lever 66 formed at one end with a bearing support 67 (Fig. 7) in which is journaled a tubular fulcrum-shaft 68. Integral with one end of the tubular fulcrum-shaft 68 is a head 69 to which is fastened by screws 70 a trimmer body-member 71 having an offset lower end 72 providing a supporting ledge for a thin knife-blade 73 of the thread-cutting and -nipping scissors device. The stationary knife-blade 73 has a sharpened knife-edge 74 (Fig. 8). Co-operating with the stationary knife-blade 73 is a movable knife-blade 75 sharpened at 76 and supported for oscillation about a pivot-screw 77 threaded into the supporting ledge 72 of the trimmer body-member 71. Positioned above the movable knife-blade 75 is a thread-nipping plate 78 secured by screws 77 and 79 and held in proper thread-nipping relation with the upper surface of the movable knife-blade 75 by spacing washers 80 and 81. An adjusting screw 82 extending through the thread-nipping plate 78

and threaded into the stationary knife-blade provides for maintaining the proper spaced relation between the blades 74, 75 and the plate 78.

The movable knife-blade 75 is formed with a shank 83 (Fig. 8) bifurcated to straddle a roller 84 carried at one end of a slide-bar 85 located in a guideway 86 formed in the body-member 71. The other end of the slide-bar 85 is enlarged and notched, as at 87, to receive the spherical end 88 of a rock-arm 89 preferably formed integral with a knife-actuating rock-shaft 90 journaled in the tubular fulcrum-shaft 68. From the foregoing it will be apparent that a rocking of the shaft 90 in one direction will close the cutting blades and at the same time nip the needle end of the thread between the movable blade 75 and the nipping-plate 78, while a rocking of the shaft 90 in the opposite direction will open the blades and release the nipped end of the needle-thread. In addition to the opening and closing of the cutting blades, the entire scissors device must be bodily moved into its intermediate needle-straddling position following which it is lowered into thread-cutting position beneath the needle. The means by which this bodily movement of the scissors device and the opening and closing of the cutting blades are obtained will now be described. The carrier-lever 66 is forked at one end to receive a slide-block 91 having a ball-and-socket connection with one end of a rock-lever 92 pinned at its other end on a rock-shaft 93 journaled in the spaced depending ears 94 (Fig. 4) formed on the base 58. Clamped on one end of the rock-shaft 93 is a lever-arm in the form of a block 95 in which is slidably mounted a spring-pressed plunger 96 having an inclined upper end 97. Cooperating with the plunger 96 is an overhanging trip-finger 98 fastened on a mounting block 99 adjustably secured by screws 100 on the sector-gear actuating link 33. A spring 101 coiled about the rock-shaft 93 and having one of its ends hooked over the rock-lever 92 functions to maintain the trimming device in its retracted or inoperative position shown in Figs. 1 and 2.

From the foregoing it will be understood that when the sector-gear actuating link 33 is moved in the direction of the arrow in Fig. 3 to disperse the stitches about the eye of the buttonhole, the trip-finger 98 engages and depresses the plunger 96, passing idly by it without actuating the trimmer. During the return movement of the sector-gear actuating link 33 when restoring the stitching devices to their initial position at the end of the rapid feed of the work-holder, the trip-finger 98 engages the plunger 96 and causes it to turn the rock-shaft 93 in a direction to raise the free end of the rock-lever 92. The raising of the rock-lever swings the carrier-arm 66 about its pivot 65, causing the trimmer device to move downward toward its thread-cutting position. Means are provided for controlling the position of the body-member 71 of the trimmer device and this means includes an arm 102 secured on the tubular fulcrum-shaft 68 (Fig. 7) and carrying at its lower end a roller 103 adapted to track an arcuate slot 104 formed in the vertical limb 64 of the angle-bracket 63. The compound motion obtained from the swinging of the carrier-lever 66 and the turning of the tubular fulcrum-shaft 68, resulting from the tracking of the roller 103 in the arcuate slot 104, imparts movement to the trimmer device such that the opened knife-blades move downwardly and forwardly into needle-

straddling position and then drop downwardly parallel to the blade of the needle to a point below the point of the needle, where the blades are then closed to sever the needle-thread. The actual closing of the knife-blades is effected by means of a cam-surface 105 formed on the edge of the vertical limb 64 of the bracket 65, which cam-surface is adapted to be contacted by a roller 106 carried by a rock-arm 107 fast on the knife-actuating rock-shaft 90. Swinging of the carrier-lever 66, in addition to positioning the knife-blades on either side of the needle and subsequently dropping them below the needle, moves the roller 106 into engagement with the cam-surface 105, which turns the shaft 90 and swings the movable blade 75 into thread-shearing engagement with the stationary blade 73. When the movable knife-blade 75 swings toward the stationary blade 73, the thread is first nipped between the bottom of the thread-nipping plate 78 and the top of the movable blade 75, following which the thread is severed. The beginning end of the thread is held until the start of the stitching devices in the next buttonholing cycle.

The means employed for opening the knife-blades to release the thread-end and to position the blades for their next thread-cutting operation, are operated by the swinging of the stop-motion lever 40 out of its stop-position, which occurs when the stitching devices are started at the end of the initial rapid feed. The means preferably includes a trimmer opening push-rod 108 (Figs. 1 and 2) secured at its inner end at 109 to the tilting stop-motion lever 40 and freely slidably adjacent its outer end in a guide 110 attached to the block 99. The outer end of the push-rod 108 is adapted to contact one limb of a bell-crank lever 111 pivoted at 112 on the base 58. The other limb of the bell-crank lever is forked to straddle a pin 113 carried at one end of a slide 114 endwise shiftable in a guideway 115 in the base 58, a retainer-plate 116 serving to maintain the slide in said guideway. At its other end, the slide 114 is formed with an L-shaped finger 117 defining an opening 118 adapted to be entered by a pin 119 projecting from a collar 120 fast on the knife-actuating rock-shaft 90. The pin 119 enters the opening 118 when the trimmer device swings upwardly from thread-cutting position, shown in full lines in Fig. 6, to retracted position, shown in full lines in Fig. 5. When the pin 119 is in the opening 118 it is in position to be engaged by the finger 117 when the slide 114 is shifted from full line position to dotted line position, Fig. 5, under the action of the push-rod 108 moving into contact with and turning the bell-crank lever 111 about its pivot 112. As shown in Fig. 5, when the pin 119 is engaged and moved by the finger 117 the knife-actuating rock-shaft 90 is turned in a direction to shift the slide-bar 85 in the body-member 71 and open the knife-blade 75.

Operation

Fig. 1 discloses the machine at rest with the work-clamp open and the beginning end of the needle-thread nipped between the movable knife-blade 75 and the cooperating thread-nipping plate 78. When work is introduced into the machine, the work-clamp is closed and automatically the buttonhole cutting mechanism is actuated, following which the rapid feed advances the work-clamp from buttonhole cutting position to stitching position. During the rapid feed the pattern-wheel 48 is turned to bring the

"start-sewing" cam 47 into contact with the follower nose 46, whereby the stop-motion lever 40 is tilted from stop position to stitching position, shown in dotted lines in Fig. 1. Tilting of the stop-motion lever 40 moves the push-rod 108 in the direction indicated by the arrow in Fig. 5. The push-rod 108 when moved endwise engages one limb of the bell-crank lever 111 causing the lever to turn about its pivot 112 and move the slide 114 from the full line position to the dotted line position, Fig. 5. In so moving, the finger 117 engages the pin 119, thereby turning the knife-actuating rock-shaft 90 in a direction to shift the slide-bar upwardly and move the knife-blade 75 into its open position. When the knife-blade 75 is moved to open position, the beginning end of the needle-thread is released and the trimming device is set for the subsequent thread-cutting operation. Preferably the trimmer is so located with respect to the needle that the released thread-end will be of a length such that it will be drawn down flush with the work in the formation of the first stitch.

When the stop-motion lever 40 is tilted, the stitching mechanism is thrown into operation to produce the first side, the eye and the return side of the buttonhole. In sewing the eye of the buttonhole the stitching mechanism is turned about a vertical axis as previously explained. In turning the stitching mechanism about the vertical axis, the sector-gear actuating link 33 moves to the right (Fig. 1) and carries with it the mounting block 99 supporting the overhanging trip-finger 98. The trip-finger 98 engages and depresses the plunger 96, passing idly by the block 95 without affecting the trimmer.

After the buttonhole is completed and the rapid feed has returned the work-holder to its loading position, the stitching mechanism is reversely turned about the vertical axis to restore it to initial stitching position. During the return movement of the sector-gear actuating link 33, the trip-finger 98 engages the side of the plunger 96 and thereby rocks the block 95 in a direction to turn the rock-shaft 93 and raise the free end of the rock-lever 92. The raising of the rock-lever 92 swings the carrier-arm 66 about its pivot 65, causing the trimmer device to move downward in the general direction of the needle 24. During the swinging of the carrier-arm 66, the roller 103 travels downward in the arcuate slot 104. The swinging of the carrier-lever 66 and the action of the roller 103 tracking the slot 104 impart a compound motion to the trimmer body-member 71 such that the opened knife-blades move into needle-straddling position, shown in dotted lines in Fig. 6, following which the trimmer device drops below the needle-point, the path of travel of the trimmer device being indicated by the dot-and-dash line in Figs. 5 and 6. During the dropping of the trimmer device from needle-straddling position to thread-cutting position, the roller 106 engages the cam-surface 105 and thereby effects a turning of the knife-actuating rock-shaft 90 in a direction to swing the movable knife-blade 75 into thread-nipping relation with the plate 78 and thread-severing relation with the stationary knife-blade 73. It will be appreciated that the needle-thread is positively admitted between the knife-blades by virtue of the fact that the knife-blades first straddle the needle with one blade on either side of the body of the needle between the eye and shank thereof and then drop to a point below the needle. It will be understood also that once the thread is

5 between the knife-blades 73 and 75 it cannot escape because the direction of movement of the trimmer device toward and from cutting position is transversely of the path of travel of the work-holder. In other words, there is no tendency for the thread to escape through the opening between the free ends of the knife-blades. It will be seen in the drawings that the thread-engaging edge of the nipping plate 78 is curved in a direction to minimize the possibility of the thread escaping by the free end of the nipping plate.

10 In order to insure that the opening 118 in the slide 114 is positioned vertically above the pin 119 so that the latter will surely enter the opening 15 when the spring 101 snaps the trimmer device into elevation or retracted position immediately following the thread-cutting operation, the block 20 95 is designed so that as it is rocked backwardly under the action of the trip-finger 98 its rear edge 25 engages the limb of the bell-crank lever 111 and reversely swings the lever into the position shown in full lines in Fig. 5. In this position the opening 118 is disposed to be entered by the pin 119 when the trimmer device swings upwardly.

25 Having thus set forth the nature of the invention, what I claim herein is:

1. A sewing machine having stitch-forming mechanism including a thread-carrying needle having an eye and a shank, work-feeding mechanism, a needle-thread trimmer device including a pair of relatively movable thread-severing blades, said trimmer device having a retracted position, an intermediate needle-straddling position in which said thread-severing blades are separated and arranged on opposite sides of said needle at a level between its eye and shank, and a thread-cutting position spaced from said needle, means for shifting said trimmer device from retracted position to needle-straddling position and 30 then to thread-cutting position, and connections for effecting a relative movement of said thread-severing blades into thread-severing relation.

2. A buttonhole sewing machine having stitch-forming mechanism including an upper thread-carrying needle having an eye and a shank and complementary under thread mechanism, a work-holder, means for relatively moving the stitch-forming mechanism and work-holder to sew about a buttonhole, connections for turning the stitching mechanism about a vertical axis to sew around the end of the buttonhole, a needle-thread trimmer device including a pair of relatively movable thread-severing blades, said trimmer device having a retracted position, an intermediate needle-straddling position in which said thread-severing blades are separated and arranged on opposite sides of said needle at a level between its eye and shank, and a thread-cutting position spaced from said needle, mechanism operatively associated with said stitching mechanism turning-connections for successively advancing said trimmer device from retracted position to needle-straddling and thread-severing position, and means for effecting relative movement of said thread-severing blades into thread-severing relation.

3. A buttonhole sewing machine having stitch-forming mechanism including an upper thread-carrying needle and complementary under thread mechanism, a work-holder, mechanism for relatively moving the stitch-forming mechanism and work-holder to sew about a buttonhole, connections for turning the stitching mechanism about a vertical axis to sew around the end of

the buttonhole, a stop-motion device for starting and stopping the stitch-forming mechanism, a shiftable needle-thread trimmer device including a pair of relatively movable thread-severing blades, mechanism operatively associated with said stitching mechanism turning-connections for shifting said trimmer into thread-severing position and for closing said blades into thread-severing relation, and mechanism operatively connected with said stop-motion device for opening said trimmer-blades.

4. A buttonhole sewing machine having stitch-forming mechanism including an upper thread-carrying needle having an eye and a shank and complementary under thread mechanism, a work-holder, means for relatively moving the stitch-forming mechanism and work-holder to sew about a buttonhole, connections for turning the stitching mechanism about a vertical axis to sew around the end of the buttonhole, a needle-thread trimmer including a pair of relatively movable thread-severing blades, said trimmer device having a retracted position, an intermediate needle-straddling position in which the blades are separated and arranged on opposite sides of the needle at a level between its eye and shank, and a thread-cutting position spaced from said needle, mechanism operatively associated with said stitching mechanism turning-connections for successively advancing said trimmer from retracted position to needle-straddling and thread-severing position, means to close the blades of said trimmer in the advancing movement of the trimmer, and spring means to return the trimmer to its retracted position following the thread-severing action.

5. A group-stitch sewing machine having stitch-forming mechanism including an upper endwise reciprocating thread-carrying needle, a work-holder, mechanism for relatively moving the stitch-forming mechanism and the work-holder to sew about a predetermined pattern, a stop-motion device for starting and stopping the stitch-forming mechanism, a needle-thread trimmer including a pair of relatively movable blades, means to close said trimmer-blades to sever the needle-thread, and means operatively connected with said stop-motion device for opening said trimmer-blades.

6. A group-stitch sewing machine having stitch-forming mechanism including an upper endwise reciprocating thread-carrying needle, a work-holder, mechanism for relatively moving the stitch-forming mechanism and the work-holder to sew about a predetermined pattern, a stop-motion device for starting and stopping the stitch-forming mechanism, a needle-thread trimmer including a pair of relatively movable blades, means to close said trimmer-blades to sever the needle-thread, a push-rod operatively connected to said stop-motion device, and blade-opening mechanism operatively associated with said push-rod.

7. A thread-trimming device for a sewing machine having a frame including an overhanging bracket-arm, comprising, a lever fulcrumed on said bracket-arm, a thread-cutting scissors device mounted on said lever and movable therewith from retracted to thread-severing position, means to close said scissors device in its advance from retracted to thread-severing position, and connections to open said scissors device when it is returned to its retracted position, said connections including a slide operatively connected to said scissors device, a lever for shifting said

slide, and an automatically actuated push-rod adapted to engage said lever.

8. A thread-trimming device adapted for a buttonhole sewing machine having stitch-turning mechanism and a stop-motion device, comprising, a base, a scissors device movably supported on said base for movement from retracted to thread-severing positions, means adapted to be actuated by said stitch-turning mechanism for advancing said scissors device to thread-severing position and closing said scissors device into thread-severing position during the advancing movement thereof, and means operatively associated with said scissors device when the latter is in retracted position for opening the same in preparation for its next thread-cutting operation, said last named means adapted to be actuated by said stop-motion device.

9. A needle-thread trimming device for sewing machines having a thread-carrying needle provided with an eye and a shank, comprising, a supporting member, a carrier lever fulcrumed on said supporting member, a shaft journaled in said carrier-lever, a trimmer device supported by said shaft and including a pair of relatively movable thread-severing blades, connections provided for swinging said carrier-lever about its fulcrum to move said trimmer device into a needle-straddling position in which the thread-severing blades are separated and disposed at opposite sides of said needle at a level between its eye and shank, means provided for turning said shaft in said carrier-lever to lower said trimmer device to a position in which the thread-severing blades are below the needle, and connections provided for effecting relative movement of said thread-severing blades into thread-severing relation.

10. A needle-thread trimming device for sewing machines having a thread-carrying needle provided with an eye and a shank, comprising, a supporting member, a carrier-lever fulcrumed on said supporting member, a shaft journaled in said carrier-lever, a trimmer device supported by said shaft and including a pair of relatively movable thread-severing blades, connections provided for swinging said carrier-lever about its fulcrum to move said trimmer device into a needle-straddling position in which the thread-severing blades are separated and disposed at opposite sides of said needle at a level between its eye and shank, means rendered effective by the swinging of said carrier-lever for turning said shaft in said carrier-lever to lower said trimmer device to a position in which the thread-severing blades are below the needle, and connections also rendered effective by the swinging of said carrier-lever for closing said thread-severing blades into thread-severing relation.

11. A needle-thread trimming device for sewing machines having a thread-carrying needle provided with an eye and a shank, comprising, a supporting member having a cam-slot and a cam-surface, a carrier-lever fulcrumed on said supporting member, a shaft journaled in said carrier-lever, a trimmer device supported by said shaft and including a pair of relatively movable thread-severing blades, connections provided for swinging said carrier-lever about its fulcrum to move said trimmer device into a needle-straddling position in which the thread-severing blades are separated and arranged at opposite sides of said needle at a level between its eye and shank, an arm secured to said shaft and having one end operatively connected to said cam-slot for turning said shaft in said carrier-lever to lower said

trimmer device to a position in which the thread-severing blades are below the needle, and connections adapted to engage said cam-surface thereby to close said thread-severing blades into thread-severing relation.

12. A needle-thread trimming device for sewing machines having a thread-carrying needle provided with an eye and a shank, comprising, a supporting member having a cam-slot and a cam-surface, a carrier-lever fulcrumed on said supporting member, a tubular shaft journaled in said carrier-lever, a trimmer device carried by said tubular shaft and including a pair of relatively movable thread-severing blades, connections provided for swinging said carrier-lever about its fulcrum to move said trimmer device into a needle-straddling position in which the thread-severing blades are separated and arranged at opposite sides of said needle at a level between its eye and shank, an arm secured to said tubular shaft and having one end operatively connected to said cam-slot for turning said tubular shaft in said carrier-lever when the carrier-lever is swung about its fulcrum to lower said trimmer device
